INERTIA OPERATED PUMP

Filed Feb. 18, 1922

UNITED STATES PATENT OFFICE.

CHESTER H. BRASELTON, OF NEW YORK, AND FRED B. MACLAREN, OF JAMAICA, NEW YORK; SAID MACLAREN ASSIGNOR TO SAID BRASELTON.

INERTIA-OPERATED PUMP.

Application filed February 18, 1922. Serial No. 537,582.

This invention relates to improvements in fuel feed apparatus of a character to be operated by vibrations imparted to the apparatus, it being particularly adapted for use in fuel feed systems for automotive vehicles.

One of the objects of the invention is the provision of means for the above purpose which shall be of simple construction, small 10 cost, and of a nature not liable to get out of order easily.

Another object of the invention is the provision of a pumping means of such character that parts slideable upon each other are 15 eliminated with a consequent elimination of friction and improvement in pumping efficiency.

Another object of the invention is the provision of a mounting for the upper end 20 of the guide for the moving column which makes accuracy in workmanship unnecessary.

Another object of the invention is the provision of a mounting for the pumping 25 apparatus at an inclination from the vertical by reason of which arrangement we are enabled to take advantage of the vertical components in certain transverse vibrations of the vehicle as well as of vertical vibrations therein.

Other objects, and objects relating to details of construction and economies of manufacture, will appear as we proceed with the description of that embodiment of our 35 invention which, for the purposes of the present application, we have illustrated in the accompanying drawings, in which:

Figure I is a diagrammatic side elevational view of an automobile equipped with 40 our improved apparatus;

Figure II is a central longitudinal sectional view of the auxiliary tank and pumping apparatus; and

Figure III is a front elevational view of 45 the dash board looking in the direction of the arrow in Figure I and showing our tank and pumping apparatus mounted at an angle.

Similar reference characters refer to like 50 parts throughout the views.

In Figure I we have illustrated the preferred arrangement of the different portions of our fuel feed apparatus upon an automobile, 10 being the main or low level 55 fuel tank, 11 the high level or auxiliary

tank and 12 the carburetor. The tank 10 is connected by means of a conduit 13 with the bottom of the tank 11 while the conduit 14 forms a connection between the carburetor 12 and the tank 11 at a position some- 60 what above the bottom of that tank.

The tank 11 is preferably cylindrical. At the central point of its base it is provided with an internally threaded collar 15 for the reception of the plug 16 to the lower end of which is adapted to be connected the conduit 13 leading to the main tank 10. The lower portion of the plug has a passage 17 the upper end of which constitutes a seat for a ball check 18 located in a chamber 19 which is closed at the top by a small threaded plug 20 having perforations there- 70 through to connect the chamber 19 with a lower compartment 21 of the tank. Within this compartment and along the wall thereof is a ring 22 having an upper flange 23 upon which is mounted by any suitable means a diaphragm 24 forming the partition between the lower compartment 21 and an upper compartment 25. 75

The diaphragm by its own resilience tends normally to assume the position shown in Figure II, but in order to assist and reinforce the diaphragm we prefer to employ a coil spring 26 bearing at its lower end upon the end wall of the tank and at its upper extremity upon the lower surface of the dia- 80 phragm.

There is attached to the center of the diaphragm by means of the fluid tight joint 90 of any suitable character an upwardly ex- 95 tends column 27 having fluid discharge passages 28 therein extending from a valve chamber 29 near the base of the column. This chamber is closed by means of a threaded plug 30 having a passage 31 there- 100 through normally closed by a spring pressed ball check 32 located in the valve chamber 29.

The column 27 is enlarged to a greater or lesser extent at its upper end and within this enlargement is formed a chamber 33. The walls of the chamber embrace with a sliding fit a guide 34 depending from the top 35 of the tank. This guide is preferably 105 made hollow for the sake of the consequent saving in weight. It is closed at its upper end by a threaded plug 36 having an upper curved surface, preferably spherical. The guide 34 is attached to the tank top by means 110

of a machine screw 37 extending through a hole in the top of somewhat greater diameter than the diameter of the screw. By virtue of this arrangement the guide has what might be termed a universal mounting enabling it to assume different angles with respect to the plane of the tank cover although within small limits as will be understood. It is thus also susceptible of being moved bodily within the limits defined by the possible movement of the screw 37 in the openings through the tank cover. By this means it is possible to obtain accurate alignment of the guide 34 and column 27 in spite of slight inaccuracies in the adjustment of the tank cover 35 with respect to the body of the tank. In practice such inaccuracies occur for instance during the assembly of the tank when certain of the screws 9 attaching the cover to the side walls are driven tighter than others.

The enlarged portion of the column 27 has a small passage 38 therethrough connecting the chamber 33 with the liquid storage portion of the tank. When pumping has proceeded far enough to fill the tank up to the level of the chamber 33, it begins to fill with liquid, the air thus displaced escaping around the sides of the guide 34. In a sense this liquid is trapped within the chamber 33, that is it can escape only through the small passage 38. When it gets high enough in the chamber 33 to be engaged by the guide 34, it tends to prevent relative motion between the tank and column, thus dampening if not stopping the pumping action.

A pin 39 extends loosely through the tank cover 35 and is threaded at its lower end into the column 27. At its upper end it carries a head 40 by means of which it is adapted to be grasped by the operator and reciprocated whenever manual operation of the pump is necessary.

Our auxiliary tank 11 and pumping apparatus may be attached to any part of the vehicle. At the present time we prefer to mount it upon the forward side of the dashboard 41. The mounting may be effected in any suitable manner such as by means of a clamping band 42. In the embodiment illustrated in the drawing the tank is set at an incline transversely of the vehicle. The inclination may be in any other plane however as will be obvious.

As a vehicle equipped with our improved apparatus travels over the road it is subjected to constant vibration both vertically and transversely, although principally vertically. We take advantage of these vibrations by providing a diaphragm which is surmounted with a column of considerable weight and of consequent relatively high inertia. The column therefore tends to remain at any given height. Any vibration

tending to move the vehicle in a direction at right angles to the diaphragm causes the tank to move against the resilience of the diaphragm and its reinforcing spring while the column tends to remain in its previous position. There is thus brought about a relative motion between the column and tank which flexes the diaphragm, causing the liquid in the lower compartment 21 to be forced upwardly through the passage 31, valve chamber 29 and passages 28 into the upper compartment 25 of the tank. The descending portion of the vibration causes the parts to assume their first position and as the ball check 32 then remains closed and the lower compartment 21 is again enlarged, the ball check 18 is lifted from its seat and fuel flows into the lower compartment due to atmospheric pressure on the top of the liquid in the main tank.

When a repetition of the above described operation has filled the tank to a predetermined level fuel flows through the small passage 38 into chamber 33 where it acts as a damper to stop or greatly diminish the pumping action.

Several features of the invention are shown in our co-pending applications, Serial No. 532,718 "inertia pumps," filed January 30, 1922, Serial No. 533,493, "vibration operated pumping mechanism," filed February 1, 1922, and Serial No. 575,886 "level maintaining means in a pumping system," filed July 18, 1922, in which we reserve the right to claim these features broadly.

What we claim as our invention is:

1. In fuel feed apparatus for automotive vehicles, a high level tank divided into upper and lower compartments separated by a diaphragm, a column of relatively high inertia extending upwardly from said diaphragm and containing a valved liquid passage connecting the two compartments, yieldable means tending to hold said column elevated, and a fluid connection between the lower compartment and a source of fuel supply.

2. In fuel feed apparatus for automotive vehicles, a high level tank divided into upper and lower compartments separated by a diaphragm, a column of relatively high inertia extending upwardly from said diaphragm and containing a valved liquid passage connecting the two compartments, yieldable means tending to hold said column elevated, a fluid connection between the lower compartment and a source of fuel supply, and means at the top of the tank for guiding said column in its vertical movements.

3. In fuel feed apparatus for automotive vehicles, a high level tank divided into upper and lower compartments separated by a diaphragm, a column of relatively high inertia extending upwardly from said diaphragm and containing a valved liquid pas-

- sage connecting the two compartments, yieldable means tending to hold said column elevated, a fluid connection between the lower compartment and a source of fuel supply, 5 and means for dampening the movements of said column when the fuel in the upper compartment reaches a certain predetermined level.
4. In fuel feed apparatus for automotive vehicles, a high level tank divided into upper and lower compartments separated by a diaphragm, a column of relatively high inertia extending upwardly from said diaphragm and containing a valved liquid passage connecting the two compartments, yieldable means tending to hold said column elevated, a fluid connection between the lower compartment and a source of fuel supply, and means at the top of the tank for 10 guiding said column in its vertical movements, said means being capable of rocking motion with respect to the tank.
5. In fuel feed apparatus for automotive vehicles, a high level tank divided into upper and lower compartments separated by a diaphragm, a column of relatively high inertia extending upwardly from said diaphragm and containing a valved liquid passage connecting the two compartments, 15 yieldable means tending to hold said column elevated, a fluid connection between the lower compartment and a source of fuel supply, and means at the top of the tank for guiding said column in its vertical movements, said means being capable of rocking motion with respect to the tank.
6. In fuel feed apparatus for automotive vehicles, a high level tank divided into upper and lower compartments separated by a diaphragm, a column of relatively high inertia extending upwardly from said diaphragm and containing a valved liquid passage connecting the two compartments, 20 yieldable means tending to hold said column elevated, a fluid connection between the lower compartment and a source of fuel supply, and means at the top of the tank for guiding said column in its vertical movements, 25 said means being capable of rocking motion in all directions with respect to the tank.
7. In fuel feed apparatus for automotive vehicles, a high level tank divided into upper and lower compartments separated by a diaphragm, a column of relatively high inertia extending upwardly from said diaphragm and containing a valved liquid passage connecting the two compartments, 30 yieldable means tending to hold said column elevated, a fluid connection between the lower compartment and a source of fuel supply, and means at the top of the tank for guiding said column in its vertical movements, 35 said means being capable of rocking motion in all directions with respect to the tank.
8. In pumping mechanism, the combination of a movable support; a tank secured to said support and movable therewith; a diaphragm within said tank and a weighted member fixed to said diaphragm adapted to vibrate the same; and means including a piston member fixed to said tank within the same and cooperating with said weighted member to dampen the vibrations imparted 40 to the weighted member by the support.
9. In a fuel feed apparatus for automotive vehicles; a supply tank; an auxiliary higher level tank; a diaphragm in said higher level tank; valve means cooperating with 45 said diaphragm to cause fuel to flow from said supply tank to said auxiliary tank when said diaphragm is vibrated; inertia actuated means to vibrate said diaphragm; and means to dampen the vibrations of said diaphragm when the fuel rises above a predetermined level in said tank.
10. In fuel feed apparatus for automotive vehicles, a high level tank divided into upper and lower compartments separated by a diaphragm, a column of relatively high inertia extending upwardly from said diaphragm and containing a valved liquid passage connecting the two compartments, 50 yieldable means tending to hold said column elevated, a fluid connection between the lower compartment and a source of fuel supply, and means at the top of the tank for guiding said column in its vertical movements, 55 said means being capable of rocking motion with respect to the tank.
11. In fuel feed apparatus for automotive vehicles, a high level tank divided into upper and lower compartments separated by a diaphragm, a cylinder of relatively high inertia extending upwardly from said diaphragm and containing a valved liquid passage connecting the two compartments, 60 yieldable means tending to hold said cylinder elevated, a fluid connection between the lower compartment and a source of fuel supply, and means at the top of the tank for guiding said cylinder in its vertical movements, 65 said means being capable of rocking motion with respect to the tank.
12. In pumping mechanism, the combination of a movable support; a tank secured to said support and movable therewith; a diaphragm within said tank and a weighted member fixed to said diaphragm adapted to vibrate the same; and means including a piston member fixed to said tank within the same and cooperating with said weighted member to dampen the vibrations imparted 70 to the weighted member by the support.
13. In a fuel feed apparatus for automotive vehicles; a supply tank; an auxiliary higher level tank; a diaphragm in said higher level tank; valve means cooperating with 75 said diaphragm to cause fuel to flow from said supply tank to said auxiliary tank when said diaphragm is vibrated; inertia actuated means to vibrate said diaphragm; and means to dampen the vibrations of said diaphragm when the fuel rises above a predetermined level in said tank.
14. In fuel feed apparatus for automotive vehicles, a high level tank divided into upper and lower compartments separated by a diaphragm, a column of relatively high inertia extending upwardly from said diaphragm and containing a valved liquid passage connecting the two compartments, 80 yieldable means tending to hold said column elevated, a fluid connection between the lower compartment and a source of fuel supply, and means at the top of the tank for guiding said column in its vertical movements, 85 said means being capable of rocking motion with respect to the tank.

In testimony whereof, we affix our signatures.

CHESTER H. BRASELTON.
